COIL GRINDING EQUIPMENT

Wallace K. Lowe, Syracuse, N. Y., assignor to
 Crucible Steel Company of America, New York,
 N. Y., a corporation of New York

Application December 6, 1950, Serial No. 199,410

10 Claims. (Cl. 51—112)

1

This invention relates to grinding and polishing machines, and more particularly to such machines wherein abrasive members are simultaneously rotated about their axes and revolved about the work interposed therebetween in pressure engagement therewith.

Apparatus has been suggested in the past for grinding and polishing elongated stock or elongated workpieces, including wire stock having in combination a rotatable supporting head which mounts a grinding wheel, the supporting head having an axially extending passage therethrough for the wire stock. In such apparatus the supporting head has been rotated about the stock and the grinding wheel revolved in planetary movement thereabout at the same time, the grinding wheel being in operative engagement therewith and being rotated upon its axis.

In such apparatus heretofore proposed, work-holding or work-rest members have been mounted in fixed or adjustable relation with said supporting head for maintaining the wire stock against lateral displacement and to urge same against the grinding wheel, there being suitable means for moving the work-holding member towards the grinding wheel whereby the wire stock can be maintained in engagement with such wheel as the latter wears away. Such prior apparatus has employed the periphery of the grinding wheel as the working surface thereof. Furthermore, such prior apparatus has employed only a single grinding wheel for planetary movement about the wire stock. It is, of course, necessary to employ a counterweight to counterbalance such single grinding wheel and to adjust same radially of the grinding head in order to compensate for wear of the wheel. As the grinding wheel is gradually worn, the mass thereof is reduced by an amount equal to the mass removed by attrition or abrasion. The counterweight for the grinding wheel does not undergo a similar reduction in mass. Consequently the extent of the radial adjustment for the grinding wheel will not be similar to the extent of radial adjustment of the counterweight for a given reduction in mass of the grinding wheel. This has introduced substantial difficulties in the balancing of the grinding wheel and has complicated the problem of radial adjustment of these parts while in motion. Furthermore, in apparatus of this character suggested in the past there has not been a satisfactory means provided for injecting grinding solution into the housing for the grinding head.

Also prior apparatus of this type heretofore

2

suggested has not been capable of as rapid and thorough grinding of the wire stock as that herein disclosed because they have employed only a single grinding wheel and, as above mentioned, only the periphery of such grinding wheel.

One of the objects of the present invention is to provide novel means for grinding a continuous coil of wire of the so-called "centerless grinder type" which means can be easily and simply adjusted to compensate for wear of the grinding surfaces.

Another object of the invention is to provide so-called self-balancing grinding means for continuously grinding elongated stock, such as a coil of wire.

Still a further object is to provide apparatus of this character, including novel means for controlling the axial movement of the grinding surfaces between which the workpiece moves.

20 The invention, in one aspect thereof, is constituted by a novel grinding head. It is normal practice to mount grinding heads at opposite extremities of a main support shaft, the latter being rapidly rotated by suitable power means 25 and having a passage extending axially therethrough for the movement of the wire stock. Novel grinding heads of the present invention are mounted one on each extremity of such a main supporting shaft and each comprises a pair 30 of grinding wheels which are mounted upon a disc-like supporting head, the latter being also termed a rotatable head. Such grinding wheels are mounted on opposite sides of the center of the supporting head in such a manner that the wire stock to be ground can pass therebetween 35 and through such axial passage in the supporting shaft. Said wheels are mounted on opposite sides of the wire stock in so-called face-to-face relationship whereby they are positioned in such a manner that the flat faces thereof 40 instead of the peripheries engage and grind the stock. Where two such grinding heads are employed, one at each extremity of a main supporting shaft as above mentioned, it is usual for the grinding head which first engages the 45 stock to provide a "roughing grind" and the latter a "finishing grind." Each grinding wheel is independently driven by a motor which may be coaxial therewith, individually connected thereto and mounted on the supporting head. Means are provided for mounting the motors and the grinding wheels secured thereto for movement along the axes of their respective grinding wheels, that is, radially of the supporting head or substantially so, whereby said grind-

ing wheels can be adjusted concurrently toward or away from the wire stock by means of a separate adjusting motor which also is mounted upon said supporting head and is operatively connected by suitable means to the axially shiftable motors. The grinding wheels preferably are mounted not precisely in parallel face-to-face relationship but with the axes thereof slightly canted relative to one another, that is, disposed so that such axes intersect at an acute angle preferably at or near the axis of the main support shaft whereby marginal portions of said grinding wheels engage the wire stock.

Various, further and more specific objects, features and advantages of the invention will clearly appear from the detailed description given below taken in connection with the accompanying drawings which form a part of this specification and illustrate, by way of example, preferred arrangements of apparatus for carrying out the invention. The invention consists of such novel combinations of features as may be shown and described in connection with the apparatus herein disclosed.

In the drawings:

Fig. 1 is a side elevation showing one form of the present invention;

Fig. 2 is a sectional view of the apparatus shown in Fig. 1 taken substantially along line 2—2 of the latter figure;

Fig. 3 is an end view, partly in section and with parts broken away, of the novel grinding head embodying one form of the present invention;

Fig. 4 is a side elevation, partly in section and with parts broken away, of a grinding head embodying one form of the present invention;

5 Referring to the drawings in greater detail, with particular reference to Fig. 1, the apparatus is constituted in general by a feed and straightening unit indicated at 20, a grinding and/or polishing unit as at 21, a control unit as at 22 and a reeling unit as at 23.

An unwinding drum or frame is provided at 24 around which the wire stock to be ground or polished is initially wound and from which it is unwound and fed into the apparatus. The wire stock is indicated at 25 and is directed first to a pinch roll unit indicated generally at 26 and which includes a pair of peripherally grooved rolls 27 and 28 between which the wire stock passes and by which said stock is urged toward the remainder of the apparatus and particularly toward a wire straightening unit 29. One or both of said pinch rolls preferably are power driven by a motor indicated at 30 through the intermediary of a reduction gear 31, the latter being connected to said rolls as by a sprocket chain 32.

15 The grinding and polishing unit 21 is constituted generally by a main supporting shaft 33 which is journaled for rotation in suitable bearings generally indicated at 34 and 35. Shaft 33 can be rotated by a suitable electric motor indicated at 36 which is operatively connected thereto by means of a worm and wheel reduction unit, indicated generally at 37, by a sprocket chain 38 which engages suitable sprocket wheels 39 and 40 respectively secured to the shaft 33 and to an output shaft of said reduction unit 37.

20 Secured to opposite extremities of shaft 33 are grinding heads 41 and 42 which may be respectively employed for a "rough" and "finish" "cut" or "grind" upon the stock 25. The grinding heads 41 and 42 are each completely enclosed by protective housings 43 and 44, respectively.

25 The motor 36 (Fig. 2) is mounted upon a main pedestal 45 which in turn supports a journal pedestal 46 upon which the journals 34 and 35 are mounted.

30 Referring now to Figs. 3, 4 and 5, and particularly to Fig. 4, it will be seen that the main supporting shaft 33 rests in a suitable sleeve bearing as of Babbitt metal 35a, the latter comprising a part of said bearing 35. At the righthand extremity of the main supporting shaft 33 (Fig. 4) the grinding head 41 is located. Said grinding head includes a so-called "supporting head" or "rotating head" 47 which is rigidly secured to the shaft 33 for rotation therewith and preferably is a disc-like member. The main supporting shaft 33 has formed therein an axial passage 33a through which the wire stock 25 can pass. As shown in Fig. 4, said wire stock is directed toward the center of the supporting head 47 and hence toward the axial passage in the main supporting shaft 33, the latter two elements being concentric. The wire stock 25 moves from right to left as viewed in Fig. 4.

35 Said grinding head 41 is provided with a pair of grinding wheels 48 and 49 which are mounted, as is well shown in Fig. 4, on opposite sides of the axis of the main supporting shaft 33 and hence similarly with respect to the supporting head 47, said wheels being in so-called face-to-face relationship wherein the faces thereof (as opposed to the peripheries) are almost parallel to one another. But, in the form shown, such faces are not quite parallel, the axes of rotation thereof

being disposed at an acute angle to one another as shown in Fig. 1. Such axes may intersect at the axis of the main supporting shaft 33 but, as is shown in Fig. 3, such axes intersect at a point slightly above the axis of shaft 33. The axes of rotation of the grinding wheels 48 and 49 are preferably coplanar although the invention is not limited thereto.

It has been determined that the efficacy of the grinding wheels, and particularly the balancing thereof, is substantially improved by so disposing the grinding wheels and by mounting them for axial movement as will be explained hereinafter.

The terms "face-to-face," as employed in describing the relative disposition of the grinding wheels 48 and 49, indicates that the portions of the grinding wheels in planes perpendicular to the respective axes of rotation thereof are substantially parallel and are situated opposite to one another in spaced relationship and substantially in register.

Individual power means are provided for rotating the grinding wheels 48 and 49 which preferably comprise electric motors 50 and 51, respectively. The rotors of such motors are, in the form shown, coaxial with and rigidly secured to their respective grinding wheels 48 and 49. However, the invention is not limited to such a relative disposition of the rotors and the grinding wheels, it being understood that such rotors may be operatively connected to such grinding wheels in any suitable manner.

The grinding wheels 48 and 49 thus are arranged to grind the wire stock 25 upon flat faces 48a and 49a (Figs. 4 and 5) rather than upon their peripheral edges 48b and 49b.

The grinding wheels 48 and 49 are mounted for axial movement, as will be hereinafter explained, in such a manner that they contact diametrically opposite surface portions of the stock 25 being ground. Also the grinding faces 48a and 49a, by virtue of the canting of the axes of the grinding wheels, are set at an acute angle to the direction of stock feed and to the axis of the main supporting shaft 33.

It will be observed that as a result of such canting of the grinding wheels the faces thereof, 48a and 49a, will become bevelled after a sufficient period of engagement with the wire stock so that an appreciably greater abrasive surface will engage the stock, as is best shown in Fig. 5 and as compared with the area of engagement as shown in Fig. 4.

As is well shown in Fig. 4, the motors 50 and 51 are mounted with the axes thereof coplanar and slightly canted, that is, at an acute angle relative to one another. Said axes intersect at a point which may be slightly removed from the axis of the main supporting shaft. Said motors 50 and 51 are mounted in a manner which is well illustrated in Fig. 5 wherein the mounting for motor 50 is shown in detail. Such mounting is constituted by a cylindrical outer housing 52 which surrounds a cylindrical inner housing 53, the latter enclosing a stator 54 and a rotor 55 which is mounted upon a rotor shaft 56. The latter mounts the grinding wheel 48.

The inner housing 53 is adapted for axial sliding movement in the cylindrical outer housing 52 but is restrained from angular movement therein by virtue of the key 57 which is secured to the housing 53 and engages a suitable groove in the housing 52.

The canting of the axes of the grinding wheel 75

48 is accomplished by securing the outer housing 52 to the supporting head 47 by means of a wedge-shaped member 58 which may be formed integral with a mounting plate generally indicated at 59 which in turn may form a part of the outer housing 52. It is preferable for the mounting plate 59 with its wedge-shaped portion 58 to engage a suitable recess formed in the supporting head 47 and to be secured therein in a well known manner, as by bolts.

It will be understood that the mounting for the motor 51 is analogous to that of motor 50. Thus each grinding wheel and its associated driving motor is mounted as a unit and is axially adjustable toward and away from the stock being ground in a manner to be explained more fully hereinafter.

Referring to Figs. 1 and 4, a coolant or a lubricant solution to facilitate the grinding is supplied to the stock at the region of abrasion by means of a supply conduit 60 having branches 61 and 62 respectively directed to the grinding heads 41 and 42. In Fig. 4 there is shown in detail novel nozzle means for directing such solution onto the region of the stock undergoing grinding and also onto the stock prior to the time it is abraded by the grinding wheels. Such nozzle means are generally indicated at 63 and are constituted by a centrally mounted nozzle 64 which preferably is frusto-conical in shape having a frusto-conical inner passage. The nozzle 64 is secured to a nozzle base 65 which is in the form of an annular sleeve member communicating with a ring 66 which is directly in communication with the conduit 61. The stock 25 passes through a suitable passageway in the ring 66, the base member 65, thence through the passage in the nozzle 64, and thence to the grinding wheels. The grinding solution thus is directed onto all sides of the wire stock 25 prior to the time that it emerges from the nozzle 64. The nozzle 64 has a mouth 64a, the inner diameter of which is slightly in excess of the diameter of the wire stock. Consequently such solution is squirted out of the nozzle 64 onto all sides of the stock being ground and is directed to a point beyond the grinding wheel, as viewed in Fig. 4. Preferably the mouth 64a of nozzle 64 is situated between the grinding wheels 48, 49.

In order to retain the solution for recirculation and reuse, a bowl member or a bowl-like retaining vessel, having an aperture formed in the center of the bottom thereof for the passage of the wire, is provided as at 67 and may be secured to the main supporting shaft 33 by any suitable means. Said aperture in the bottom of the bowl member 67 is shown as at 68, the latter being in register with the axial passage 33a formed in the shaft 33. As is well shown in Fig. 4, the bowl-like member is also provided with circular openings situated in diametrically opposed locations for the reception of so-called neck flanges 50a and 51a of the motors 50 and 51, respectively. Such circular openings are indicated at 69 and 70. Flanges are formed around said openings as at 69a and 70a, respectively, for embracing closely said neck flanges 50a and 51a, respectively, whereby the coolant or grinding solution is prevented from leaking past said flanges. The bowl 67, as shown in Fig. 4, extends from the extremity of shaft 33 to the right somewhat beyond the grinding wheels 48 and 49, there being an outwardly flared mouth of the bowl

provided at 67a which is designed for cooperating with a fixed portion of the housing 43. The above-described nozzle means 63 preferably is held in the position shown in Fig. 4 by means of a stationary shell 43a which preferably is circular in cross-section as taken in a plane perpendicular to the axis of the wire stock 25. Said shell 43a is rigidly secured to the remainder of the housing in any suitable means as by the flanged interconnecting member 71. The shell 43a is provided with an inwardly turned edge as at 43b which forms a stationary annular flange for cooperating with a rotating annular flange 67b formed at the outer margin of the mouth 67a of the bowl 67. The shell 43a cooperating with the bowl 67 retains substantially all of the solution ejected from the nozzle 64; said solution collecting in the shell 43a from 67 and being conducted therefrom by means of a recovery conduit 72 in communication therewith.

A bowl (not shown) similar to bowl 67 is employed analogously in the grinding head 42 and cooperates with a shell 44a which is analogous to said shell 43a. A suitable recovery conduit for the grinding solution is provided at 73 for conducting same away from the shell 44a.

Suitable hand controlled valves, as at 74, 75, are interposed respectively in the conduits 61 and 62 for controlling the volume of such solution directed upon the workpiece.

Referring again to Fig. 5, the means for associating the grinding wheel 48 with the motor 50 will now be described. Said grinding wheel 48 is mounted upon a metal plate 76 by means, for example, of suitable nuts 77 and bolts 78. The mounting plate 76 is secured to a bed plate or motor disc 79 by any suitable means, such as bolts, one of which is shown at 80. The disc 79 is formed with a central bore for the reception of the outer extremity of the motor shaft 56, such extremity being indicated at 56a. A shoulder 56b preferably is formed on said shaft to the left of the portion 56a, as viewed in Fig. 5, upon which said plate 79 rests and is held thereagainst by means of a cap plate 81 and bolts 82.

The motor shaft 56 is provided with roller bearings 83 for absorbing radial thrusts, said bearings 83 being at the righthand extremity of the shaft, as viewed in Fig. 5, and thus near that extremity of the shaft 56 which supports the grinding wheel 48.

The grinding wheel 48, in order to engage the wire stock 25, may be urged to the right (Fig. 5) and consequently a suitable thrust bearing as at 84 is provided for communicating thrust in such direction to the shaft 56 and hence to said grinding wheel. For aiding in disengaging the grinding wheel from the wire stock or in moving same to the left (Fig. 5), a suitable bearing is provided for communicating thrust to the left from the housing to the shaft 56, such bearing being provided at 85. The inner ring of bearing 85, may, if desired, be rigidly held to the shaft 56 by means, for example, of an end plug 86. However, the operative interconnection between said bearing and the housing of the motor for communicating thrust to the left may include a bearing plate as at 87 which surrounds the shaft 56 and by suitable shoulders at 88 contacts the outer ring of said bearing, said bearing plate 87 being operatively associated with the housing 53 by means of yielding members comprising springs 89 which sur-

round arms 90, the latter being connected to the bearing plate 87.

The stationary outer race or ring of the bearing 83 is preferably embraced by a flanged bearing plate 91. The latter is secured to an annular or ring-shaped member 92 by any suitable fastening means as at 93. Member 92 preferably is rigidly secured, as by welding, to the inner housing 53. The inner face of the ring 92 is provided with a stepped surface 92a for the reception of a bearing plate 94, the latter being removable for disassembly purposes upon the unfastening of the means 93 and the removal of the bearing plate 91. The bearing plate 94 provides along the inner margin thereof a shoulder for communicating thrust to one of the rings of the bearing 84, said thrust being to the right (Fig. 5) and being communicated to the shaft 56 via the other ring of bearing 84 and via a flanged sleeve 95, the latter engaging the shoulder 56b via the inner race of the bearing 83.

There will now be described the novel means for controlling concurrently the axial positions of the grinding wheels 48 and 49 by axial movement of the motor housings. Such means for housing 53 for the motor 50 is shown in Fig. 5. A portion of the outer cylindrical surface of the inner housing 53 is threaded, as at 53a, and such threaded portion is embraced by an annular shaped gear 96 having a toothed periphery and a threaded inner surface, the latter being designed for threaded engagement with said threaded portion 53a. It is clear, if suitable means, comprising for example the key 57, are provided for preventing angular movement of the inner housing 53 and for preventing axial movement of the gear 96, that angular movement of the latter will be translated into axial movement of the housing 53 and hence the grinding wheel 48 which is axially movable therewith. The means for restraining said gear from axial movement comprise, in the form shown, a pair of flanges 97 and 98 which are situated fixedly adjacent opposite faces of the gear 96. The flange 97 preferably is formed integral with the outer housing 52 and surrounds the latter. The flange 98 is rigidly secured relative to the flange 97 by any suitable means whereby there is no relative movement therebetween. It has been found desirable to interpose suitable bearings between the flanges 97 and 98 and the gear 96. For example, a bearing ring 99 is interposed between the flange 97 and the gear 96 and a suitable ball bearing as at 100 is interposed between the flange 98 and said gear, the latter bearing having been found desirable in order to assist in urging the grinding wheel to the right as viewed in Fig. 5 and against the wire stock.

Referring to Fig. 3, the annular gear 96 is shown in connection with the motor 50 and an analogous gear 101 is shown in connection with motor 51, the latter being operatively associated with this motor in a manner analogous to that of gear 96. Means are provided for simultaneously shifting said gears 96, 101 angularly in order to move the grinding wheels 48, 49 axially in opposite directions. Said means are constituted in the form shown by a common adjusting motor 102 (Figs. 3, 6 and 7) which is securely mounted upon the supporting head 47, as is well shown in Fig. 6, wherein said motor 102 is supported in a suitable aperture near the margin of said supporting head 47. The motor 102 communicates torque simultaneously to said gears 96 and 101 by an operative interconnection consisting of the following: A

worm 103 secured to a shaft 104 of the motor 102 is in engagement with a worm wheel 105 which is keyed to a shaft 106. To the latter shaft there is also keyed a pinion gear 107 which meshes with a pinion gear of substantially larger diameter as at 108, the latter in turn being in keyed engagement with a supporting shaft 109. The elements 103-108 thus constitute a reduction gear train for very substantially reducing the R. P. M. of the motor 102. Because of the above-described canting of the axes of the motors 50 and 51 and the grinding wheels 48 and 49, it is necessary to employ universal couplings 110 and 111 for respectively interconnecting the shaft 109 with the remaining portions of the operative interconnection to said gears 96 and 101. The universal coupling 110 communicates the torque of shaft 109 to a shaft 112 mounted in a suitable bracket 113 and having secured thereto a chain sprocket gear 114. The latter, by means of a chain belt 115, interconnects the gear 114 to a chain sprocket 116, the latter in turn being secured to a shaft 117 upon which there is also secured a pinion gear 118 which meshes with said gear 96.

The coupling 111 for the gear 101 is operatively interconnected to the latter by analogous means. It is understood that the threading upon the inner housings of the motors 50 and 51 is such that actuation of the motor 102 will cause the grinding wheels to move axially and concurrently in opposite directions.

The slip ring structure for communicating electrical energy to the three motors comprising parts of each grinding head is well shown in Figs. 8-11, inclusive. For example, in Fig. 8 the slip ring structure for grinding head 41 is indicated generally at 119 and for grinding head 42 at 120. Each slip ring unit is constituted by six separate slip rings mounted in suitable insulation to insulate same from one another and from a bearing sleeve 33b which embraces the shaft 33, the sleeve 33b being interposed between the shaft 33 and the above-described bearing therefor.

As is well shown in Fig. 10, a portion of the electrical interconnection between slip rings 119a, 119b and the motor 50 is shown. Said slip rings 119a and 119b are connected to said motor by means of suitably insulated wires 121 and 122 which are secured respectively thereto and which pass through a suitable passage 33c formed in the bearing sleeve 33b.

The next pair of slip rings 119c, 119d is connected to the motor 51 by analogous means, and the pair of rings 119e and 119f is also connected analogously to the adjusting motor 102.

Said slip rings 119a-119f, inclusive, surround a common insulating sleeve 123 (Fig. 11) which embraces the bearing sleeve 33b. Said rings have interposed therebetween spacers as at 124. The slip ring assembly is held together by means of end flanges 125, 126 which are secured to one another by means of suitable bolts as at 127.

Upon the control unit 22 (Fig. 1) suitable electrical control units are located for governing the speeds of the grinding wheel motors, such as 50, 51, and also for controlling the adjusting motors, such as 102.

In operation, the grinding wheels are separated by a sufficient distance to permit free passage of the wire stock 25 while the latter is being threaded through the machine whereupon the motor 36 is started for rotating the grinding wheels planetarily around the wire stock, at which time the adjusting motors, such as 102, may be actuated to move the grinding wheels,

such as 48, 49, to a point where they engage the wire stock, the motors of the grinding head 41 being adjusted for a "rough cut" and the motors for the head 42 being adjusted for a "finish cut."

Due to the high reducing action of the gear train and the related operative interconnection between the adjusting motor, such as 102, and the inner housing of the motors 50, 51, it is possible to control the movement of the grinding wheels with substantial accuracy because a single revolution of the motor 102 provides a very minute axial movement of said grinding wheels. During operation the coolant or grinding solution is continuously directed into the grinding heads and is recovered in the recovery bowls therein and directed to suitable means for recirculating same. As the grinding wheels wear down, their mass is reduced as hereinabove mentioned, but such wearing down will be at a common rate for both wheels whereby the change in mass will be equal for both and consequently there is a so-called "self-balancing" action. By simple adjustment of the motor 102 said wheels are moved concurrently in equal but opposite amounts thereby properly adjusting same. Suitable means can be provided for continuously measuring the diameter of the wire stock at a point near the region of abrasion thereof and for controlling each adjusting motor as at 102 in accordance therewith whereby there can be an automatic control of the axial position of the grinding wheels of a single pair relative to one another. Thus there can be provided a so-called "automatic sizing device." In lieu of such automatic control, the axial position of the grinding wheels of a single pair thereof can be controlled from the control panel 22.

In the embodiment of the invention shown in Fig. 1, the main supporting shaft 33 is a continuous member without any means for separating same, for example, into halves to facilitate the installation of sprocket chain 38. Thus in order to remove the sprocket chain 38 from the apparatus, as shown in Fig. 1, it is necessary to disassemble a major portion of the apparatus and to remove the chain via one of the extremities of the shaft 33, or alternatively to disassemble a link in said chain whereby the latter may be separated and removed from its sprocket wheels as at 39 and 40. In the modification shown in Fig. 12, means are provided for removing the chain 38 from the gear 39 and separating same from the apparatus by providing separable portions of the main supporting shaft. Thus a modified main supporting shaft is indicated generally in Fig. 12 at 128 and is constituted by separable half portions 128a, 128b. At 60 the inner or adjacent extremities of half portions 128a, 128b there are provided sleeves or collars 129 and 130 which may be rigidly secured together by any suitable means, such as the bolts 131. One of the collars, such as 129, is provided with a peripheral surface as at 129a on which is mounted in keyed engagement therewith an annular sprocket member 132 which is analogous to the sprocket wheel 39 (Fig. 2). An end flange 130a on the collar 130 is so constructed and arranged that it cooperates with the collar 129 for holding the sprocket member 132 in position on said periphery 129a against a flange 129b when the two shaft halves 128a, 128b are bolted together as shown in Fig. 12. Thus in order to remove a belt or chain 38 from

around member 132 it is necessary only to remove bolts 131, separate the collars 129, 130, and slide member 132 to the left (Fig. 12) off of periphery 129a.

The shaft half portion 128a, in the form shown, is constituted by a main bearing shaft 128c which is journaled in suitable bearings as at 133 which support same in the manner of a sleeve bearing and is provided with an end bearing flange 133a which is designed for engaging a collar 47a of the supporting head 47. Such end flange 133a acts in the nature of a thrust bearing when the device is assembled for operation.

If desired, the interconnection between the main bearing shaft 128c and the collar 129 may be accomplished by an interconnecting shaft 128d which extends into a recess 128e of shaft portion 128c and is in keyed engagement with the latter. The collar 129 embraces said interconnecting shaft 128d and is also in keyed engagement therewith. Thus the collar 129 and the main supporting shaft 128c can shift axially of the interconnecting shaft 128d by virtue of their keyed engagement therewith. Any suitable means may be employed for retaining the constituent parts of shaft 128 in their position shown in Fig. 12 whereby such axial motion is prevented. For example, suitable conventional means may be employed for removably securing each main supporting portion against axial motion.

Thus when it is desired to disassemble the apparatus or when it is desired to remove the sprocket chain 38 therefrom, such disassembling or removal is facilitated by the above-described association of shaft parts (Fig. 12). It is understood that the lefthand half 128b of the shaft 128 is constructed analogously to shaft half 128a.

It has been found desirable, although the invention is not limited thereto, to employ means giving support to the wire stock at the region where such stock is undergoing grinding at each grinding head. Such supporting means are shown in Figs. 13-15 and comprise a pair of flat plate-like fingers 134 and 135 which are designed to extend between the grinding wheels 48, 49, as in Fig. 15. The plate-like supporting finger 135, as shown in Figs. 13 and 15, extends beneath the wire stock 25 over substantially the full width of the grinding face 48a. The fingers 134 and 135 are provided with wire stock supporting faces 134a and 135a, respectively, which are held in spaced relationship to the stock at a distance which is slightly greater than the diameter of such stock 25 but is sufficiently close to hold same firmly during the grinding action.

Said supporting fingers 134, 135 are secured to the rotating head 47 for rotation therewith and are spaced equidistant from the axis of rotation thereof. Such supporting means are shown in Fig. 13 and are constituted by a mounting 136 having a threaded portion 136a which engages a suitable threaded recess formed in the rotating head 47 and which may be held firmly in such threaded engagement by a bolt 137 which secures a flange 136b to the rotating head 47. The fingers 134, 135 act not only as supports for the stock at the region of contact with the grinding wheels but also serve to scrape the stock with a rotary motion thereby aiding in cleaning same.

As shown in Fig. 15, the thickness of the supporting fingers 134, 135 is substantially less than the diameter of the wire stock 25, for example, of the order of one-half such diameter although

such thickness may be greater providing it is not so great as to engage the grinding wheels.

A modification of the nozzle means for directing the coolant or lubricant solution to the wire stock undergoing grinding is shown in Figs. 16 and 17 and is generally indicated at 138. Such nozzle is provided with a frusto-conical or funnel portion 139 having a hollow frusto-conical interior 139a and a tip orifice 139b through which passes the wire stock 25. The frusto-conical nozzle portion 139 is secured to a nozzle base 140 which in turn is rigidly held by a portion of the housing 43a. The nozzle base 140 is provided with a relatively wide central passage 140a which is substantially larger than the diameter of the wire stock 25. At the inner or lefthand extremity of said nozzle base there is supported a stock guide 141 having interconnecting conical chambers 141a and 141b formed in opposite extremities thereof through which the stock passes. The neck portion of the guide at 141c fits loosely around the stock 25 and provides ample clearance for the passage thereof, however, it embraces the wire stock sufficiently closely to prevent passage 25 of any substantial amount of grinding solution.

The grinding solution is directed onto the stock through the nozzle portion 139 via a plurality of passages 142 which are formed in the nozzle base 140 at equal intervals therein. The grinding solution reaches such passages via an end chamber 143 (Fig. 16) which communicates with all of the inlets of such passages.

The nozzle tip orifice 139b is substantially greater in inner diameter than the diameter of the wire stock thereby providing ample space for the passage of the grinding solution which issues therefrom toward the stock supporting fingers 134, 135.

The embodiments of the invention above described are particularly directed to the grinding of round wire stock wherein the grinding wheels, as at 48, 49, rotate on their respective axes and engage the round stock as in Fig. 4, such grinding wheels also revolving planetarily about the axis of the stock due to the rotation of the shaft 33 (or 128). However, it is possible to grind, for example, parallel sided bar stock of polygonal cross section by holding stationary the shaft 33 or 128, that is, by preventing the main supporting shaft from rotating and by passing the stock between the rotating grinding wheels of the grinding heads. Both of the grinding heads may be relatively angularly disposed to abrade the same pair of parallel opposed surfaces of such polygonal bar stock or different pairs of such surfaces. For example, the grinding heads 41 and 42, as shown in Fig. 1, are relatively angularly arranged to grind the same pair of opposite parallel surfaces of polygonal bar stock.

It is understood that the pinch rolls 26 and the straightener unit 29 are not employed when grinding polygonal bar stock but instead a suitable pair of power driven pinch rolls, as at 26a (Figs. 18, 19) are preferably employed which are capable of grasping opposite parallel surfaces of such stock as at 25a and urging same toward the grinding heads.

In the embodiment of Fig. 1, the relative angular disposition of the grinding heads can be adjusted, for example, by adjusting the angular positions of one of the rotating supporting heads as at 47 relative to shaft 33. Such adjustment of the relative angular positions of the grinding heads can also be made in the modification of Fig. 12 by removing the bolts 131, making a suitable

relative angular adjustment between the collars 129 and 130 (and hence shaft halves 129a, 129b) and thereupon reinstalling the bolts 131 with their accompanying nuts. Such an adjustment is shown in the modification of Fig. 18.

For example, in grinding bar stock 25 of square cross section it has been found advantageous to have one pair of grinding wheels set at right angles to the other pair as in Fig. 18 whereby both pairs of parallel opposite surfaces of the bar stock can be ground in one pass through the apparatus.

In addition to eliminating the pinch rolls 26 and the straightener 29, it may be desirable to attach so-called bar holding fixtures or racks 144 for supporting such bar stock as it is moved to and from the apparatus.

It is also possible to grind round bar sections in addition to the grinding of so-called continuous coils. That is, round bar sections of substantial diameters, for example, up to two inches, can be ground by this apparatus.

There is thus provided novel apparatus for the grinding of continuous wire coil stock or round bar stock and also for the grinding of stock of any polygonal configuration having parallel sides, the grinding of such widely different types of stock being possible with a single apparatus. I have found that this apparatus has substantially increased productive capacity over previously suggested continuous coil grinders. Due to the novel automatic characteristics of this apparatus and its increased productive capacity, it accomplishes a substantial saving in the cost of labor. Furthermore, such steels as high speed and tool steel compositions can be surface ground and guaranteed to be free of surface decarburization.

While the invention has been described with respect to a certain preferred example which has given satisfactory results, it will be understood by those skilled in the art after understanding the invention that various changes and modifications may be made without departing from the spirit and scope of the invention, and it is intended therefore in the appended claims to cover all such changes and modifications.

What is claimed as new and is desired to be secured by Letters Patent is:

1. In a grinding machine for wire stock, the combination with a rotatable head support of a pair of grinding wheels mounted on said support for planetary movement about the axis of a central passage formed in said support through which the stock can pass, said wheels being mounted face-to-face by means including a pair of grinding wheel support shafts rigidly secured to respective of said grinding wheels, journal means for supporting said grinding wheel support shafts for both axial and angular movement, drive means for said support shafts and grinding wheels, an adjusting motor secured upon said rotatable head support, mechanism for operatively interconnecting said adjusting motor with each of said grinding wheel support shafts for exerting a common thrust upon such shafts in opposite directions, said shafts being axially shiftable in equal and opposite directions thereby, a control device for said adjusting motor remotely situated relative thereto, and electrical interconnecting means between said motor and control device including slip rings and brushes, said adjusting motor being operable by said control device during rotation of said rotatable head support.

2. A continuous wire coil grinding apparatus comprising in combination: a main supporting shaft; and a grinding head including a pair of grinding wheels, a pair of electric motors for driving respective of said grinding wheels, means for mounting said wheels in face-to-face relation on opposite sides of the center of said head, there being a passage for the wire through said shaft along the axis of rotation thereof, a pair of outer housings for supporting respective of the housings of said electric motors for axial movement, said grinding wheels being secured respectively to a pair of grinding wheel shafts comprising respectively the shafts of said electric motors, mechanism for axially shifting said motor housings within said outer housings including an adjusting motor, and means for operatively connecting the latter to such motor housings.

3. In apparatus for grinding a length of wire, a main supporting shaft mounted for rotation, said shaft having a passage therethrough for the movement of the wire, the passage being formed axially of the shaft, a grinding head support secured to said shaft for rotation therewith, a pair of grinding wheels each having a grinding face and each being rotatably mounted upon said support with the grinding faces thereof facing one another on opposite sides of the passage through said shaft, means for mounting each of said wheels for axial movement, and mechanism mounted on said support for simultaneously moving said wheels axially toward and away from one another, said mechanism comprising electrical power means and an operative interconnection between the last-named means and said wheels for exerting axial thrust upon the latter selectively toward the axis of said main supporting shaft or away therefrom.

4. In a wire grinding apparatus the combination comprising: a main shaft having power means drivably connected thereto for rotating same, said shaft having an axial passage formed therein for the passage of the wire; and a grinding head secured to said shaft for rotation therewith comprising a head support, a pair of grinding wheels having grinding faces, said wheels being rotatably mounted on said support with the face of one positioned opposite the face of the other, the planes of rotation thereof being slightly tilted from a perpendicular relation to the plane of rotation of said support whereby the wire moving in said passage moves between said wheels and is engaged by an outer marginal area of such wheels, a pair of grinding wheel shafts rigidly secured to respective of said grinding wheels, journal means for supporting said grinding wheel shafts for axial movement, power means for driving each of said wheels, separate mechanism including electrical power means mounted on said support, mechanism for operatively interconnecting said electrical power means and said grinding wheel shafts for shifting the latter axially in opposite directions in response to energization of said power means, a control device for said electrical power means, such device being located in a position remote from said power means, and means for electrically interconnecting said control device and said electrical power means including slip ring and brush means, said electrical power means being controllable by said control device during rotation of said main shaft.

5. In a continuous wire coil grinding apparatus having a main supporting shaft and a

pair of rotatable supporting heads mounted at opposite extremities of such shaft, there being an axial passage through such supporting heads and shaft for the wire, the combination therewith of a pair of grinding wheels mounted upon each supporting head for planetary movement about the wire, each wheel having driving means operatively associated therewith for rotating same, means for mounting said grinding wheels of each pair with the axes thereof intersecting and disposed at an acute angle, the wheels of each pair being disposed on opposite sides of the center of its respective supporting head and in face-to-face relationship, said means for mounting said grinding wheels including mechanism for supporting same for axial movement along the axes of rotation thereof, power means mounted upon each of said supporting heads and operatively associated with said mechanism for actuating same and thereby simultaneously axially adjusting the position of the grinding wheels of each pair thereof.

6. In a grinding machine for elongated stock, the combination comprising: a grinding head support member, means for rotatably mounting said support member, a pair of grinding wheels each having grinding faces which are rotatable in a plane perpendicular to the axis of rotation of the wheel, said wheels being secured to said head support for revolution planetarily about the axis of the latter, there being a passage formed axially of said head support for the passage of the wire stock and about which said wheels can move planetarily with at least a portion of the face of each wheel engaging the stock, power means for each of said grinding wheels, mechanism mounted on said head support for simultaneously shifting said grinding wheels axially and in opposite directions, and an actuator device mounted also upon said head support for said mechanism for actuating same whereby the spaced relation of the faces of said grinding wheels can be adjusted for controlling the pressure of said wheels upon the wire stock passing therebetween, said actuator device comprising a common adjusting reversible electric motor operatively connected to said mechanism for axially shifting said grinding wheels.

7. In a grinding machine for elongated stock, the combination with a pair of head supports of a main supporting shaft therefor having an axial passage therethrough for the movement of the stock, said shaft being constituted by separable portions which are removably secured to one another intermediate the extremities thereof, said separable portions being angularly adjustable relative to one another, a pair of grinding wheels mounted upon each of said rotatable head supports, said wheels being mounted face to face on opposite sides of the passage through said main supporting shaft, the stock passing between said wheels for grinding, means for mounting said wheels for axial movement, power means for driving said wheels, mechanism mounted on each of said supports for simultaneously moving said wheels axially thereof in opposite directions, and means operable during rotation of said head supports for actuating said mechanisms.

8. In a grinding machine for elongated stock, the combination with a pair of head supports of two pairs of rotatable grinding wheels mounted one pair on each of said supports in face-to-

face relation, means for mounting said pairs of grinding wheels for angular adjustment relative to one another, means for mounting said wheels for axial movement, and mechanism mounted upon each of said supports for simultaneously moving the grinding wheels of each pair thereof axially in opposite directions.

9. In a continuous wire coil grinding apparatus having a main supporting shaft and a rotatable supporting head mounted at one extremity of such shaft, there being a passage extending axially through such supporting head and shaft for the wire, the combination therewith of a pair of grinding wheels mounted upon such supporting head for planetary movement about the wire, each wheel having driving means operatively associated therewith for rotating same, means for mounting said grinding wheels with the axes thereof intersecting and disposed at an acute angle such grinding wheels being disposed on opposite sides of the center of said supporting head and in face-to-face relationship, said means for mounting said grinding wheels including mechanism for supporting same for axial movement along the axes of rotation thereof, power means mounted upon said supporting head and operatively associated with said mechanism for actuating same and thereby simultaneously axially adjusting the position of said grinding wheels.

10. In a continuous wire coil grinding apparatus having a main supporting shaft and a rotatable supporting head mounted at one extremity of said shaft, there being a passage extending axially through such supporting head and shaft for the wire, the combination therewith of a pair of grinding wheels mounted upon such supporting head for planetary movement about the wire, each wheel having driving means operatively associated therewith for rotating same, such grinding wheels being disposed on opposite sides of the center of said supporting head and in canted face-to-face relationship, means for mounting said grinding wheels upon said supporting head including mechanism for effecting axial movement along the axes of rotation thereof, power means mounted upon said supporting head and operatively associated with said mechanism for actuating same, and control means operatively connected to said power means and located relatively remote from the latter for controlling same during rotation of said supporting head thereby simultaneously to adjust axially the position of such grinding wheels relative to the wire stock passing through said passage.

WALLACE K. LOWE.
